UNITED STATES PATENT OFFICE.

HAMPTON P. RHODES, OF HOUSTON, TEXAS, ASSIGNOR TO RHODES MASTER PACKING COMPANY, OF HOUSTON, TEXAS, A CORPORATION OF TEXAS.

PROCESS OF FORMING METALLIC PACKING.

Application filed October 4, 1924. Serial No. 741,777.

My invention relates to a process of constructing and forming flexible metallic packing for use in packing stuffing boxes about moving shafts, rods and the like.

5 I am convinced that a superior form of metallic packing may be made by the forming of a heavy layer of metallic ribbon about a flexible core with or without lubricant included therein. The present method of 10 winding the metallic strips, forming the body of the packing, about the center is not only expensive but results in a packing easily mutilated and worn in use.

It is an object of my invention to evolve 15 a method of securing the metallic layers about the core in the construction of the type of packing referred to, which will cause said strips to interlock longitudinally of the core without winding. Another object 20 of the invention is to provide for constricting the metallic ribbons or strips about the central core in mutually interlocked condition by a continuous operation.

In the accompanying drawings:

25 Figure 1 is a plan view of the apparatus employed in carrying out the invention, the view being of a more or less schematic nature.

Figure 2 is a view partly in side elevation 30 and partly in vertical section, illustrating the apparatus more or less schematically and likewise illustrating the manner in which the metallic strips are assembled about the central core.

35 Figure 3 is a transverse sectional view through the finished packing.

Figure 4 is a schematic view illustrating 40 the manner in which the strips are initially brought together in mutually overlapping positions.

Figure 5 is a similar view illustrating the manner in which the strips are initially distorted and constricted.

45 Figure 6 is a similar view illustrating the manner in which the strips are further distorted and constricted.

I contemplate forming a packing composed of a central core 1 of flexible and 50 compressible material such as rubber, asbestos, flax, and the like formed to extend longitudinally of the packing strip. The strips 2 of metal such as lead, babbitt or the like are arranged longitudinally of the packing and in mutually interlocked relation 55 about the core 1. I may, if desired, mix a

suitable lubricant with the ribbon or may have a plurality of cords or threads of fibrous material such as asbestos or flax 3 in which is incorporated a suitable lubricant. I also prefer to place a fabric covering 60 4 about the assembled packing to hold it in shape and protect it. Such covering may be placed thereon by any method now in common use.

In the drawing I have illustrated the 65 means by which the strips of metallic ribbon may be assembled about the central core and compressed in such a manner as to interlock. With special reference to Fig. 2 which is more or less diagrammatic I have illustrated 70 an outer conical shaped former 6 of metal or other rigid material, which serves the purpose of guiding the strips 2 of metal ribbon into position and constrict the same. The former 6 surrounds and encloses a second 75 former member which is indicated by the numeral 7 and is likewise of conical form, the two formers being concentrically arranged and being provided at their upper or minor ends respectively with throats 6^a and 7^a. The formers 6 and 7 are supported in any suitable manner above a base or platform 8.

Mounted on said platform 8 are a plurality of brackets 9 each of which has two 85 upright arms supporting a spindle 11 upon which is rotatably mounted a spool to receive the spools 10. These brackets 9 are mounted upon the platform in an irregular line about the axis of the two formers. The 90 manner of spacing these spools and their brackets is shown best in Fig. 1. The arrangement is such that the strips of metal 2 which are wound on said spools may be drawn upwardly between the conical formers 95 to interfit and overlap in the manner shown in Fig. 4.

I contemplate leading the central core 1 of the packing upwardly axially within the conical former 7 so that it will pass vertically upward through the opening 7^a at the upper end of said former 7. I further contemplate employing a plurality of cords or strands 3 of fibrous material and to saturate these strands with some lubricating liquid. 105 These strands are to be spaced uniformly in the body of the packing, as shown in Fig. 3. Where other lubricant in the body of the packing is not provided, it is believed that 110 sufficient lubrication can be included within

these strands to serve all ordinary purposes. As will be noted in Fig. 2, these cords may be arranged at spaced intervals to be drawn outwardly with these strips of metal ribbon 5 into the body of the packing.

The metallic strips 2, together with the strands 3, are led upwardly between the formers 6 and 7, in the carrying out of the method, and as they travel upwardly, being drawn in such direction by pairs of oppositely positioned rolls 12 and 13, they will be drawn together or constricted, the metallic strips being longitudinally distorted and folded medially as they pass through the opening 6^a at the upper end of the former 6, due to the restricted space between the upper ends of the formers, it being observed that the taper of the formers is such that the space between the formers is gradually decreased or diminished in the direction of the upper ends of the said formers. As the metallic strips are thus constricted and distorted, they will be interlocked with one another substantially in the manner shown in Figures 5 and 6 of the drawings, and they will likewise be constricted about the strands 3. The next step in the method consists in compressing the constricted assemblage comprising the metallic strips 2, the strands 3, and the central core 1, it being understood that the central core is led upwardly through the opening 7^a in the former 7, as previously stated, and that the strips 2, at the time they are constricted and distorted, will be automatically assembled about the core, as shown in Figure 3.

If a cylindrical packing is desired, the periphery of each roll will be semi-circular in cross section, but if the packing is to be approximately square in cross section, the peripheries of the rolls will be U shape in cross section. Above the rolls any well known mechanism may be arranged to form a fabric cover 4 on the packing as is sometimes done with packing material.

In the operation of forming the packing, the spools with the strips of metal ribbon thereon are arranged as described, the ribbon from each spool being threaded upwardly between the formers 6 and 7, to issue from the top of the guide thus formed in approximately cylindrical form. The cords 3 of wicking will be drawn upwardly with

the other material by the rollers 10 between which the metal ribbon is passed. As the strips 2 issue from the upper end of the conical formers between the rolls 12, they are crushed together about the core 1 in the manner shown in Fig. 3. The rollers serve to compress the strips of ribbon into compact relation, each strip interlock with the other adjacent strips so that they will not readily be torn apart. When thus formed into a compact section of a packing they may be covered about with the fabric covering as previously described.

The advantages of this type of packing lie in the fact that it is very easily flexible in any direction, and is subject to pressure from any side in use without tending to mutilate the packing. It is more resilient than is packing wherein the strips are wound tightly about the center core spirally as is customarily done. It will also be noted that the packing is formed in this manner by one simple process without the necessity of winding back and forth along the central core as is necessary in the usual type of wound packing. It is therefore believed that the packing thus formed is not only superior in its action when being used, in that it is more resilient and compressible without injury, but also that it is capable of being formed more cheaply and economically than is the usual type of packing.

Having thus described my invention, what I claim as new and desire to protect by Letters Patent is:

A method of forming a flexible packing comprising feeding a core longitudinally, simultaneously forming an envelope for said core by leading a plurality of flexible strips from spaced sources of supply into contact with said core while applying pressure against both the inner and outer surfaces of said envelope as it is being formed to interfold said strips with each other and thereby compact and constrict said envelope about said core, and finally pressing and shaping the assemblage into a desired cross section.

In testimony whereof I hereunto affix my signature this 24 day of September A. D. 1924.

HAMPTON P. RHODES.
